COMBINATION REED CLEANING AND POLISHING MACHINE

Walter Bixby, Boston, Mass., assignor to Shawmut Engineering Company, Boston, Mass., a corporation of Massachusetts

Application June 17, 1954, Serial No. 31,059

Term of patent 14 years

(Cl. D37—1)

Fig. 2.

Fig. 1 is a front perspective view of a combination reed cleaning and polishing machine embodying my new design.

Fig. 2 is a fragmentary perspective view of the opposite or rear side of the housing shown in Fig. 1.

The essential features of my design reside in the portions shown in full lines.

I claim:

The ornamental design for a combination reed cleaning and polishing machine, substantially as shown and described.
